GEORG SCHOENNER, OF NUEREMBERG, GERMANY.

DRAWING-PEN.

SPECIFICATION forming part of Letters Patent No. 768,153, dated August 23, 1904.

Application filed February 4, 1904. Serial No. 192,003. (No model.)

To all whom it may concern:

Be it known that I, GEORG SCHOENNER, manufacturer, a subject of the German Emperor, residing at Nuremberg, in the Empire of Germany, (whose full postal address is 7 Gartenstrasse, Nuremberg, aforesaid,) have invented certain new and useful Improvements in Drawing-Pens, of which the following is a specification.

This invention relates to an improvement in the kind of ruling-pens in which the blades while in use may be allowed to spring apart and be cleaned without adjusting the screw regulating the thickness of the lines.

This invention has for its object to simplify as far as possible the handling of such ruling-pens and to provide a locking and releasing mechanism for the spring-blades, which when the drawing-pen is in use is not cumbersome or in the way of the draftsman.

Two forms of construction of the arrangement are shown in the accompanying drawings, Figure I being an elevation; Fig. II, a side view, partially in section; Fig. III, an elevation of another form of construction; and Fig. IV, a side view, partially in section, showing the blades sprung apart.

One spring-blade, *a*, carries a set-screw *b*, which is provided in the usual manner at its lower end with a thickened head *c* and a thinner neck joining on above the head. On the inner side of the lower spring-blade *e* a small disk *d* is revolubly mounted, which when the drawing-pen is in a position for use engages the thickened head of the set-screw. For this object a concentric slot *h* is provided in the disk *f* at a distance determined by the distance of the set-screw from the pivot *g*, on which the disk turns, which slot *h* fits over the neck *d* behind the thickened head *c*, and there-

by draws the upper spring-blade *a* against or toward the lower one. In order to allow of the thickened head *c* passing through the disk *f*, the end of the slot has an enlargement *i*, corresponding in size to the diameter of the head *c*. As shown, however, in Figs. III and IV, the arrangement may be such that the slot is open at one side, thus giving the disk a hook-shaped form. In the form of construction shown, in which the disk is arranged between the two spring-blades, the lower spring-blade has a perforation *k*, in which the thickened head *c* fits when the pen is ready for use. In order that the grooved neck of the set-screw may be made as short as possible, while keeping the disk of sufficient thickness, the slot *h* is enlarged on its under side to a size corresponding to the diameter of the thickened head, which enlargement extends approximately to about half the thickness of the disk.

I declare that what I claim is—

A drawing-pen comprising a disk *f* pivotally mounted on a blade *e* which disk when turned forward in one direction fits by means of a slot *h* over the thickened head *c* of the set-screw *b* mounted in the other blade *a*, the disk *f* thereby holding the blades in the position for use, but which disk on being turned back again releases the set-screw and thereby allows the blades to spring apart to a sufficient extent for their more convenient cleaning, substantially as described.

In witness whereof I have hereunto set my hand in presence of two witnesses.

GEORG SCHOENNER.
